E. E. HARPER

DRY MATERIAL FEEDING MACHINE

Filed Dec. 7, 1925

UNITED STATES PATENT OFFICE.

ELMER E. HARPER, OF KANSAS CITY, MISSOURI.

DRY-MATERIAL-FEEDING MACHINE.

Application filed December 7, 1925. Serial No. 73,943.

My invention relates to dry material feeding machines and more particularly to those adapted for use in municipal water plants, laundries or elsewhere, for delivering measured quantities of lime or other powdered material to a raw water supply, either still or flowing, to soften or otherwise treat the water; the present invention constituting an improvement on the machine for which Letters-Patent of the United States, No. 1,546,069, were issued to me on July 14, 1925, and having for its principal objects to obviate packing of the material in the bin and to assure accurate, regulated feed of the powdered material.

In accomplishing these objects I have provided improved details of structure, the preferred forms of which are illustrated in the accompanying drawings wherein:

Fig. 1 is a perspective view of a dry material feeding machine embodying my improvements, parts being broken away for better illustration.

Fig. 2 is a detail view, partly in section, of the agitator and feeder shaft, illustrating the adjustable mounting of the feeder arm.

Referring more in detail to the drawings:

1 designates a frame within which the operating parts of the machine are mounted and preferably consisting of angle iron legs 2 supporting a material bin platform 3 consisting of angle bars welded or otherwise permanently secured to the legs 2 and to which the floor 4 may be secured by bolts 5.

Seated on the floor 4 is a bin or tank 6 which may constitute a cylinder having the floor 4 for a bottom, the floor having a port 6 near one edge of the platform through which material may be delivered from the bin, as presently described.

Located above the platform 3 is a second platform 8 also preferably consisting of angle irons 9 secured to the frame legs 2 and supporting a floor 10.

Journalled in bearings 11 and 12 on the platforms 3 and 8 is a vertical shaft 13, and mounted on the bearing 12 is a reducing gear mechanism indicated by the housing 14, which may comprise a worm gear (not shown) meshing with a worm indicated by the housing 15 and which may be fixed to a shaft 16 driven from a pulley 17 by a belt 18 on a pulley 19 fixed to the shaft 20 of a motor 21 mounted on the platform 8.

The shaft 13 extends below the floor 4 of the lower platform and is provided directly above the floor with an aperture 22 through which a rod 23 is projected to extend oppositely from the shaft directly above the floor 60 to serve as an agitator for material contained within the bin, the rod being held in place by a set screw 24 carried by the shaft.

Below the floor of the lower platform the shaft 13 is provided with an aperture 25 65 through which a feeder arm 26 is projected and in which the feeder arm is held in adjusted position by a set screw 27 that extends into a socket 28 (Fig. 2) in the shaft opening to the aperture 25 so that the set 70 screw may engage the rod 26 to hold the rod in place by an extended contact of the set screw with the rod. The rod 26 is adapted for projection over a table 29 on a bracket 30 secured to the platform 3 by bolts or the like 31; the table being so dimensioned and located as to receive material from the bin through the port 6 and carry a limited quantity of such material thereon, the arrangement being such that material dropping 80 through the port will stack on the table without escaping over the sides thereof except when forced thereover by the rod 26 when the latter is moved over the table.

Within the frame 1, beneath the platform 85 3, is a tank 32 containing raw water for treatment by the dry material which is delivered to it in measured quantities by the mechanism just described. I have illustrated a tank as the container for raw water, 90 merely for purpose of explanation, it being apparent that any other container for still water may be employed, or that the material may be delivered into a flowing stream of the water without departing from the spirit 95 of the invention.

In use of machines of this character for delivering powdered lime or such material, the material has a tendency to pack in its storage bin, thereby interfering with the delivery of measured quantities of it to the water to be treated. While the agitator rod 23 serves to break up the pack in the bottom of the bin, it not infrequently happens that an agitator of this kind will excavate beneath the mass of material in the bin and then rotate idly in the excavation, the material remaining packed above the agitator. To break up this upper pack I provide a supplemental agitator consisting of a verti- 110

cal plate 33, pivotally mounted at about its center point on a bolt or the like 34 extending through the wall of the bin and spaced therefrom by a washer 35. The upper end of the plate carries a stud 36 which projects slidably through a slot 37 in a link 38 pivotally mounted on and suspended from an arm 39, one end of which is pivotally mounted on a pin 40 on a bracket 41 on a cross arm 42 extending between legs 2 of the frame 1, the free end of the arm 39 extending over the bin and having a fork 43 straddling the vertical shaft 13. Fixed on the shaft 13 within the fork 43 is a cam 44 adapted for alternate engagement with opposite arms of the fork to rock the arm 39 and link 38 for the purpose of reciprocating the agitator plate 33 so that the latter will constantly work in the material contained within the bin 6 and prevent or break up the packing of the dry material within the bin, so that it may flow continuously through the bin and be delivered through the port 6.

Assuming the parts to be constructed and assembled as described, operation is as follows:—

The frame is arranged over the raw water supply so that the material dropping onto the table 29 may be forced from the platform into the water. The dry material is filled into the bin 6, part of it dropping through the port onto the table 29, where it stacks but does not escape into the water. The motor is then operated, driving the vertical shaft through the gear reduction; rotation of the shaft reciprocating the agitator 33 and arm 23 to effect a continuous flow of material through the outlet port onto the table. Simultaneously with the operation of the agitators, the arm 26 is moved over the table, scraping measured quantities of powdered material off the table and into the water, this operation continuing until the powdered material has been exhausted from the bin.

It is apparent that with this arrangement, packing of the material within the bin is prevented and a measured delivery of the material to the water is effected.

Measurement of delivery of material from the table may be regulated by extension of the arm 26 over the table, and if more material than can be delivered with a single scraper arm 26 is desired, a longer arm may be employed to extend from both sides of the shaft 13, so that a scraping action occurs at each half revolution of the shaft; or additional arms may be provided.

While I have shown and described specific mechanical elements, variations may be made in the specific structure and the machine may be employed for uses other than the softening or other treatment of water if desired.

What I claim and desire to secure by Letters-Patent is:

1. A machine of the character described, comprising a bin having an opening in the bottom thereof, a stationary shelf-like member mounted exteriorly of said bin and below said opening adapted to receive material from said bin through said opening, a rotatable shaft, and an arm extending laterally outwardly from said shaft and rotating therewith, said arm sweeping over said shelf-like member to move material over the edge thereof.

2. A machine of the character described, comprising a bin having an opening in the bottom thereof, a stationary shelf-like member mounted exteriorly of said bin and below said opening adapted to receive material from said bin through said opening, a rotatable shaft, and an arm extending outwardly from said shaft and rotating therewith, said arm sweeping over said shelf-like member to move material over the edge thereof, said arm being adjustable relative to said shelf-like member to regulate the amount of material moved off said shelf-like member with each sweeping movement thereof.

3. A machine of the character described, comprising a bin having an opening in the bottom thereof, a stationary shelf-like member mounted exteriorly of said bin and below said opening adapted to receive material from said bin through said opening, a rotatable shaft, and an arm extending outwardly from said shaft and rotating therewith, said arm sweeping over said shelf-like member to move material over the edge thereof, said arm being adjustable to vary the lateral extension thereof from said shaft.

4. In a machine of the character described, a bin having an outlet port, feeding mechanism for delivering measured quantities of material escaping from said port, an agitator within the bin, a shaft rotatable within the bin and cam mechanism operable by said shaft for actuating the agitator.

5. In a machine of the character described, a bin having an outlet port, a shaft rotatable within and below the bin, a feeder arm on said shaft for delivering measured quantities of material escaping through said port, an agitator within the bin, and cam mechanism operable from said shaft for actuating the agitator.

6. In a machine of the character described, a bin having an outlet port, a shaft rotatable within the bin, means operable by the shaft for feeding material delivered through the outlet port, an agitator plate pivotally mounted within the bin, a rocker arm connected with said plate, and a cam on said shaft in operable relation with said arm.

7. In a machine of the character de-

scribed, a bin, a shaft rotatable in the bin, an agitator plate pivotally mounted within the bin, a rocker arm connected with the agitator plate, a cam on said shaft and a fork on said rocker arm engageable by the cam to rock the arm and actuate the agitator plate.

8. In a machine of the character described, a bin having an outlet port, a shaft rotatable in the bin, means on the shaft for feeding material delivered through said port, a vertical agitator plate pivotally mounted within the bin and having a stud thereon at one side of the pivotal mounting, a rocker arm, a link on the rocker arm having a slot receiving said stud, a cam on the shaft and a fork on the rocker arm embracing the cam for the purpose set forth.

9. In a machine of the character described, a bin having an outlet port, a stationary table adapted for receiving material from said port, a vertical shaft in said bin extending through the bottom thereof and rotating always in the same direction, and a pair of

arms on said shaft, one immediately above the bottom of said bin and the other movable over said table.

10. In a machine of the character described, a bin having an outlet port, a table adapted for receiving material from said port, a rotatable shaft in said bin an agitating arm on said shaft rotating therewith in said bin and an auxiliary agitator pivoted adjacent the wall of said bin having a back and forth rocking motion on its pivot above 35 said arm in the bin.

11. In a machine of the character described, a bin having an outlet port, a table adapted for receiving material from said port, a rotatable shaft in said bin, an agitating member on said shaft rotating therewith in said bin and an auxiliary agitator pivoted adjacent the wall of said bin actuated by said shaft to pivotally reciprocate within said bin as said first agitator rotates. 40 45

In testimony whereof I affix my signature.

ELMER E. HARPER.
